SLIDER FOR SLIDE FASTENERS

Charles K. Deutsch, Spring Valley, N. Y.

Application February 15, 1946, Serial No. 647,881

2 Claims. (Cl. 24—205.14)

1

This invention relates in general to slide fasteners, and more particularly to the slider element which constitutes the opening and closing member of such fasteners.

An important object of my invention is to provide a slider for fasteners of the type mentioned with a locking element which firmly secures the slider in any adjusted position and yet permits the ready release of the locking element by the mere operation of the pull tab associated with the slider.

Another important object of my invention is to provide a slider which is separable or adjustable to permit easy removal of cloth or other material that may be lodged between the guide plates of the slider.

The novel features characteristic of my invention are set forth with particularity in the appended claims. The invention itself, however, both as to its construction and mode of operation together with other objects and advantages thereof, will best be understood by reference to the following description taken in connection with the accompanying drawing in which:

Fig. 1 is a view in front elevation, on an enlarged scale, of a portion of a slide fastener embodying features of my invention;

Fig. 2 is an exploded view, in perspective, showing the component parts which constitute the slider according to my invention;

Fig. 3 is a side elevational view of the slider removed from the fastener and showing the slider in locked or adjusted position;

Fig. 4 is a view similar to that of Fig. 3 but showing the slider in unlocked position; and

Fig. 5 shows a closed portion of the slide fastener, with the slider removed, to better show the position of the locking prongs or detents in relation to the fastener elements.

Referring first to Fig. 1, the slide fastener comprises a pair of tapes or stringers 1, which are provided along their opposed fastening edges with the usual beaded or corded edges 2, on which are mounted a plurality of fastener elements 3. These are of conventional type and comprise heads having interlocking means, such as projections on the upper side and recesses on the lower side, and having also outwardly extending jaws 4 which are clamped on the beaded edges 2. The interlocking elements 3 are engaged or disengaged in a well-known manner by means of a suitable slider member generally designated 5.

Referring now to the remaining figures of the drawing, the slider 5 is seen to comprise a lower guide plate 6 provided with upwardly extending

side flanges 7 and an upper guide plate 8 provided with downwardly extending side flanges 9. The lower guide plate 6 is further provided at one end with an integrally-formed wedge-shaped member 10 which serves to separate or disengage the interlocking fastener elements, and upwardly extending from the wedge separator is a threaded stud 11, rigidly retained therein.

The upper guide plate 8 is formed with an aperture 12 through which the stud 11 is adapted to extend, and on the under surface of this guide plate there is provided a transverse, downwardly extending rib 13 which is adapted to fit into a transverse groove 14 formed in the wedge 10. Formed integrally with, or otherwise attached to, guide plate 8, is a longitudinally extending ridge 15, and adapted to overlie the ridge is a locking member 16 which is pivoted on the ridge by means of a rivet or pin 17 forced into registering apertures 18 and 19 in the ridge and locking member, respectively.

The part of the locking member that overlies the ridge is channel-shaped, as shown, to receive the ridge, and formed integrally with the locking member at its formed end are a pair of pointed prongs or detents 20—21, disposed one on each side wall thereof and in staggered relation. In the upper guide plate and also in staggered relation are provided a pair of apertures 22—23, through which the detents 20—21 of the locking member are adapted to extend. At its end opposite to the detents the locking member is formed with a ring-shaped part 24 which is aligned with the upwardly extending stud 11.

An internally-threaded post 25 is adapted to pass through the ring part 24 and to be screwed onto the stud 11. Pivotaly supported near the top of the post at 28 is a pull tab 26, the side arms of which are slightly extended at 27 beyond the pivotal point 28 for a purpose hereinafter to be explained.

In Fig. 3 the component parts of the slider described above are shown in assembled condition, with the pull tab substantially horizontal. By means of a coil spring 29 surrounding the post 25 and interposed between guide plate 8 and ring 24, the locking member 16 is urged, in the illustrated position of the pull tab, to its locked position whereat the detents 20, 21 extend through their respective apertures 22, 23 in the upper guide plate. As shown in Fig. 5, the pointed ends of the detents penetrate into the corded edges 2 of the stringers to provide positive locking means of the slider 5 with respect to the fastener.

In order to disengage the locking member to

enable the slider to be moved in either direction, preparatory to effecting engagement or disengagement of the interlocking elements 3 of the fastener, the pull tab 26 is moved upwardly to a substantially vertical position, as shown in Fig. 4, and in so doing the locking member 16 is rocked about its pivotal point 17 to the raised position shown by the camming action of the pull tab arm-extensions 27, 27 on the locking member ring 24. The slide 5 is now free to be moved to a new position along the fastener, and upon the release of the pull tab, the action of coil spring 29 is such that the locking member and the pull tab are returned to their respective positions as shown in Fig. 3.

As often happens with slide fasteners of the general type herein described, the cloth or other material to which the stringers are attached becomes lodged between the upper and lower guide plates, or between the fastener elements, so that movement of the slider is difficult and sometimes impossible. With a slide member embodying my present invention it is a simple matter to overcome the above mentioned difficulty. One or two turns of the post 25 by means of the pull tab 26 causes a sufficient separation between the upper and lower guide plates to effect easy removal of the lodged material, after which the guide plates are returned to their normal operative positions by turning the post in the opposite direction. In extreme cases the guide plates may be completely separated from each other and then reassembled for use in the usual manner.

It is believed that the construction and operation, as well as the advantages of my improved locking and separable slider, will be apparent from the foregoing detailed description. It will also be apparent that while I have shown and described my invention in a preferred form, changes and modifications may be made in the structure disclosed without departing from the spirit of the invention, as sought to be defined in the following claims.

What I claim is:

1. A slider for a slide fastener of the type having interlocking elements attached to opposed stringers comprising separable upper and lower guide plates between which the stringers are adapted to be retained, said guide plates adapted to be slidably moved along the stringers to cause engagement of the interlocking elements in the movement of the guide plates in one direction and their disengagement in the movement of the guide plates in the opposite direction, a threaded post carried on the lower guide plate, the upper guide plate having an aperture through which the threaded post is adapted to extend, an internally threaded cap cooperating with the post so that when rotated in one direction to a home position the two guide plates are clamped together to assume their normal operative condition and when rotated in the opposite direction said guide plates are separable to varying degrees, a member provided with detent means pivotally mounted on the upper guide plate, said latter guide plate being provided with aperture

means through which the detent means is adapted to extend and to engage the stringers to thereby lock the slider against movement with respect to the interlocking elements of the slide fastener, and a pull tab pivotally linearly mounted on the cap for moving the slider and for rotating the cap to thereby effect adjustment between the slider guide plates, said pull tab being provided with means which upon coaction with the detent member effects the release of the detent means from its locked position.

2. A slider for a slide fastener of the type having interlocking elements attached to opposed stringers comprising separable upper and lower guide plates between which the stringers are adapted to be retained, said guide plates adapted to be slidably moved along the stringers to cause engagement of the interlocking elements in the movement of the guide plates in one direction and their disengagement in the movement of the guide plates in the opposite direction, the upper guide plate being provided with an aperture at one end, a threaded upright post carried at the corresponding end of the lower guide plate and extending through the aperture of the upper guide plate, a cap in threaded engagement with the upright post, said upright post and cap constituting means which in one position of adjustment of the cap with respect to the post maintain the guide plates in a clamped operative position and in another position of adjustment of the cap with respect to the post provides adjustable spacing between said plates, a member pivotally mounted at an intermediate point on the upper guide plate, said member having detent means at one end and a ring part at the other end which encircles the cap and upright post, spring means surrounding the cap and upright post and interposed between the ring part and the upper guide plate to urge the detent means through the aperture means in the upper guide plate for locking the slider against movement, a pull tab pivotally mounted on said cap for operating the slider, said pull tab upon rotation thereof causing rotational movement between said cap and post to effect adjustment between the slider guide plates, and cam means formed on said tab which upon being raised to slide-operating position cause the cam means to coact with the ring part of the locking member to rock said member about its pivotal point to thereby effect its release from the locked position.
